UNITED STATES PATENT OFFICE.

EDWARD A. SEVERANCE, OF BURLINGTON, VERMONT.

ELECTROPLATING BARREL AND CATCHER.

Application filed June 30, 1921. Serial No. 481,522.

To all whom it may concern:

Be it known that I, EDWARD A. SEVERANCE, a citizen of the United States, residing at Burlington, in the county of Chittenden 5 and the State of Vermont, have invented a new and useful Electroplating Barrel and Catcher, of which the following is a specification.

My invention relates to electro-plating 10 and has reference more particularly to plating barrels and a catcher therein, an object being the provision of an improved plating barrel whereby the operation of plating is reduced to a minimum and the time required 15 is also reduced to a minimum.

Another object is the provision of a catcher whereby the plated articles may be thoroughly drained and quickly removed from the barrel in bulk.

With these and other objects in view my 20 invention consists in certain novel features of construction arrangement and combination of parts as will be hereinafter described and pointed out in the claims, reference being had to the accompanying drawings forming a part hereof, in which,

Figure 1 is an end elevation showing the apparatus ready for operation.

Figure 2 is a longitudinal section showing 30 the catcher in place.

Figure 3 is a vertical section of the tank and barrel showing position of the articles before being picked up by the barrel.

Figure 4 is a vertical section of the barrel 35 after revolution through 180° showing picking-up process completed.

Figure 5 is a longitudinal section of the barrel with catcher removed and closure in place.

Referring more specifically to the drawings 40 10 indicates the tub or tank in which the plating solution 11 is placed.

Within the tank is supported the barrel 45 which comprises the heads 12 suitably connected. 13 are bars forming cathodes. 14 is a shaft which also acts as connector for the cathodes wires 15, and upon this shaft is mounted the driving pulley 16.

Interchangeable bars 17 are used to hold 50 the covering material 18 of the barrel, which cover material may be either canvas or cloth.

The anodes 19 are hung on metal bars 20 at opposite sides of the tank, said bars being held within the spaced apart projections 21 55 at each end of the tank. Negative contact is secured by means of the heavy lever 22 hav-

ing the brush 23 thereon which is brought into contact with the shaft 14, which as stated connects the cathodes 13 through the wires 15.

The catcher which is an important feature of the invention consists of the ends 24 connected by the lower side bars 25 and the sheet metal top 26 which is inclined from the top of one side downwardly to the opposite 60 side where it meets the side 27 which is of reticulated material such as woven wire, this side being continued to form the bottom 28 of the catcher; the bottom 28 continues up to about one half the height of the opposite 65 side 29, leaving an entrance or throat 30 to the catcher.

One end of the catcher is provided with a handle 31 by which it is inserted and removed from the barrel and the handle is secured to the catcher being substantially bow-shaped so that it can be readily grasped.

The catcher when in use in the barrel is mounted on guides 32 which are preferably of angle shape, as seen in Figures 3 and 4, and these guides are rigidly supported and held within the barrel on the end cleats 33 secured to the opposite heads or ends of the barrel.

One head of the barrel is provided with an opening 34 through which the catcher is introduced and when the catcher is not in place this opening is closed by a cover door 35, which is provided with the pivoted resilient latch bar 36, the ends of which will be frictionally held by the bails 37 as shown in 80 Figure 1.

The operation of the apparatus is as follows:

The barrel is placed in the tank which is filled with a plating solution and the articles 95 to be plated are first prepared as usual and then placed in the barrel through the end opening 34; this opening is closed by the cover door 35 before the current is turned on. The barrel is now rotated at a slow 100 rate until the plating is completed. The cover door 35 is now removed and the catcher is introduced into the barrel sliding on the guides 32, with the free end of the top 26 of the catcher fitting closely to the inside of the barrel so that none of the articles can slip by when the barrel is again rotated.

The catcher now being in place the barrel is rotated in the direction of the arrow and the articles indicated generally by A will 110 be scooped up by the inclined top 26 and deposited within the catcher and carried up

to the position indicated in Figure 3; in this position the catcher is held stationary a sufficient length of time to allow the surplus solution to drain off through the reticulated bottom 28.

One revolution of the barrel is sufficient to pick up all the articles and after the draining operation is completed the catcher is withdrawn from the barrel and the plated articles removed therefrom.

The above set forth process can then be repeated.

What I claim is:

1. An electro-plating apparatus comprising in combination, a solution tank, anodes disposed within said tank at the side thereof, a rotatable barrel comprising end heads and a textile covering between said heads, said heads rigidly secured to a drive shaft mounted in said tank, cathode bars held within said barrel and in circuit with said shaft, movable brush means mounted on said tank and adapted to be contacted with said shaft, and a reticulated work catcher removably mounted within said barrel.

2. An electro-plating apparatus comprising a solution tank, a plating barrel rotatably mounted in said tank, means for supplying current to the interior of the barrel, an anode extending into said tank adjacent the barrel, and a work catcher removably mounted in said barrel.

3. In an electro-plating apparatus of the character described, a barrel comprising a pair of heads and a flexible covering, and a removable work catcher mounted in said barrel.

4. In an electro-plating apparatus of the character described, a plating barrel comprising a pair of heads and a cover of textile material between said heads, one head provided with an eccentrically disposed opening or doorway therethrough, and a reticulated work catcher removably mounted in said doorway and within the barrel.

5. In an electro-plating apparatus of the character described and including a rotatable plating barrel of textile material, a work catcher removably mounted within said barrel, said catcher comprising a reticulated open sided trough adapted to extend from end to end of the barrel.

6. An electro-plating apparatus of the character described and comprising a rotatable work holding barrel provided at one end with an eccentrically located aperture or opening, and means inserted through said aperture and sustained within said barrel, adapted to pick up the plated articles placed within the barrel and carry them up for collection when the drum is given one complete revolution in one direction.

7. An electro-plating apparatus of the character described comprising a rotatable work holding barrel provided at one end with an eccentrically positioned aperture, guide ways extending between the ends from said aperture, means for closing said aperture, and an open sided trough removably mounted on said guide ways, said trough adapted to catch and lift the plated articles within the barrel to position for removal of the trough with the articles by a single complete revolution of the barrel in one direction.

8. An electro-plating apparatus as recited in claim 7, the trough comprising a reticulated bottom and sides, and an obliquely disposed top.

9. An electro-plated apparatus as recited in claim 8, the trough including bottom support bars and to be movably seated on guideways within the barrel.

10. An electro-plating apparatus as recited in claim 7, the trough being supplied with a top of imperforate metal, said top extending obliquely from the upper end of one side of the trough and defining a longitudinal throat or opening in the opposite side whereby the said top will act as a scoop to catch and deposit the plated articles in the trough, when the barrel is rotated in one predetermined direction.

EDWARD A. SEVERANCE.
